US00D755384S

(12) **United States Design Patent**
Pesce et al.(10) **Patent No.:** **US D755,384 S**
(45) **Date of Patent:** **** May 3, 2016**(54) **STENT**(71) Applicant: **Edwards Lifesciences CardiaQ LLC**,
Irvine, CA (US)(72) Inventors: **Luca Pesce**, Huntington Beach, CA
(US); **J. Brent Ratz**, Winchester, MA
(US)(73) Assignee: **Edwards Lifesciences CardiaQ LLC**,
Irvine, CA (US)(***) Term: **14 Years**(21) Appl. No.: **29/484,001**(22) Filed: **Mar. 5, 2014**(51) LOC (10) Cl. **24-02**

Primary Examiner — Susan Bennett Hattan

Assistant Examiner — Charles Hanson

(57) **CLAIM**

The ornamental design for a stent, as shown and described.

DESCRIPTION

FIG. 1 is a top and back perspective view of an embodiment of the stent.

FIG. 2 is a top view thereof, the bottom and sides being mirror images.

FIG. 3 is a front view thereof; and,

FIG. 4 is a back view thereof.
